(57) **CLAIM**

The ornamental design for a medicine injector, as shown and described.

DESCRIPTION

FIG. 1 is a perspective front view of a medicine injector; FIG. 2 is a front elevation view thereof; FIG. 3 is a rear elevation view thereof; FIG. 4 is a left side elevation view thereof, the opposite side being a mirror image; and, FIG. 5 is a top plan view thereof.

The broken line showing the environment in the drawings is for illustrative purposes only and forms no part of the claimed design.
